CLAIM

The ornamental design for an organizer label clip, as shown and described.

DESCRIPTION

FIG. 1 is a perspective view of an organizer label clip showing my new design;

FIG. 2 is a front view thereof;

FIG. 3 is a back view thereof;

FIG. 4 is a top view thereof;

FIG. 5 is a bottom view thereof;

FIG. 6 is a side view thereof; and,

FIG. 7 is an opposite side view thereof.

In FIGS. 3, 6, and 7, the broken lines showing of environmental structure for purposes of illustrating the organizer label clip. The broken lines and the structure they depict form no part of the claimed design.

The broken lines in the figures depict portions of the clip that form no part of the claimed design.
